(57) **CLAIM**

The ornamental design for an energy module with a backplane connector, as shown and described.

DESCRIPTION

FIG. 1 is a perspective view of an energy module with a backplane connector.

FIG. 2 is a front elevation view of the energy module with the backplane connector of FIG. 1.

FIG. 3 is a rear elevation view of the energy module with the backplane connector of FIG. 1.

FIG. 4 is a left elevation view of the energy module with the backplane connector of FIG. 1.

FIG. 5 is a right elevation view of the energy module with the backplane connector of FIG. 1.

FIG. 6 is a top plan view of the energy module with the backplane connector of FIG. 1; and,

FIG. 7 is a bottom plan view of the energy module with the backplane connector of FIG. 1.

The wire frame lines shown throughout the views are intended to indicate surface contour.

The broken lines in the drawings illustrate portions of the energy module with a backplane connector that form no part of the claimed design.
